UNITED STATES PATENT OFFICE.

FRANK A. DOWLING, OF CLEVELAND, OHIO.

DESIGN FOR A SPOON, &c.

SPECIFICATION forming part of Design No. 22,778, dated September 12, 1893.

Application filed June 28, 1893. Serial No. 479,101. Term of patent 3½ years.

To all whom it may concern:

Be it known that I, FRANK A. DOWLING, a citizen of the United States, residing at Cleveland, in the county of Cuyahoga, State of Ohio, have invented and produced a new and original Design for Spoons or Forks, of which the following is a specification, reference being had to the accompanying drawing, showing a part thereof.

10 The figure is a front elevation of a spoon with tines of a fork in dotted lines, showing my design for the handle.

15 The leading feature of my design consists in the peculiar configuration of outline of the handle, and in the embossed surface comprising figures in relief of two turkeys within the scrolled margin of the upper end of the handle and next beneath these, a basket of fruits and flowers at the upper end of a cor-

20 nucopia, which extends downward, forming the outline and surface of this part of the handle, and beneath this, to the bowl of the spoon or fork, the handle is curved, and has a scrolled margin or border, within which is

25 a panel for any suitable inscription.

A is the upper end of the handle which is in scrolled contour having a series of scrolls forming the outline and border.

B B are turkeys, the first one representing a strutting turkey with tail spread and wings drooping; the second one representing a hen turkey.

C represents a basket of fruits and flowers forming the upper end of a cornucopia D, which extends downward forming the outline and surface of this part of the handle.

E is the portion of handle extending from said cornucopia to the bowl of a spoon or fork, having on its surface within the border a panel for any suitable inscription.

Having described my design, I claim—

The design for handles of spoons or forks substantially as shown and described.

FRANK A. DOWLING.
